(57) **CLAIM**

The ornamental design for a shower filter housing, as shown and described.

DESCRIPTION

FIG. 1 is a side view of the shower filter housing illustrating my new design;

FIG. 2 is an opposite side view of the shower filter housing;

FIG. 3 is a top view of the shower filter housing;

FIG. 4 is a bottom view of the shower filter housing;

FIG. 5 is a front view of the shower filter housing;

FIG. 6 is a rear view of the shower filter housing; and,
FIG. 7 is a perspective view of the shower filter housing showing my new design.

The shower head and shower water pipe with pipe cover shown in dashed lines in FIG. 7 are included for environmental purposes only and form no part of the subject design.
